RUBBER MILL FRAME

James T. Matsuoka, Brecksville, Ohio, assignor, by mesne assignments, to Stewart Bolling & Co., Inc., Cleveland, Ohio, a corporation of Ohio

Filed July 20, 1967, Ser. No. 7,900

Term of patent 14 years

U.S. Cl. D55—1(9)
Int. Cl. D15—05

FIG. 1 is a top plan view of a rubber mill frame embodying my new design;

FIG. 2 is an end elevation view thereof;

FIG. 3 is a side elevation view of the left side of the design shown in FIGS. 1 and 2; and

FIG. 4 is a side elevation view of the right side of the design shown in FIGS. 1 and 2.

I claim:

The ornamental design for rubber mill frame, substantially as shown and described.
